UNITED STATES PATENT OFFICE.

ROBERT H. WALLER, OF NASHVILLE, TENNESSEE, ASSIGNOR TO QUICKSAFE MANUFACTURING COMPANY, OF NASHVILLE, TENNESSEE, A CORPORATION OF TENNESSEE.

CAN OPENER.

Application filed May 17, 1922. Serial No. 561,651.

To all whom it may concern:

Be it known that I, ROBERT H. WALLER, a citizen of the United States, residing at Nashville, in the county of Davidson and 5 State of Tennessee, have invented a new and useful Can Opener, of which the following is a specification.

This invention relates to can opening devices of that class which employ a rotary 10 cutter in cooperation with a gage roller adapted to run along the inside of the bead of the can, with the bead clamped between the cutter and roller, whereby the can is positively rotated when the cut is being 15 made; and the specific improvement consists in means for automatically throwing the cutter into cooperative cutting relation with the gage roller when the cutter is rotated in one direction, and for automatically throwing 20 the cutter out of operation when the cutter is rotated in a reverse direction. By this means, the bead of the can may be more readily inserted in position and the construction of the can opener is simplified and 25 made much more rugged and capable of performing its work.

The invention will be best understood from a consideration of the following detailed description taken in connection with 30 the accompanying drawing forming part of this specification, with the understanding, however, that the invention is not confined to any strict conformity with the showing in the drawing, but may be changed and 35 modified so long as such changes and modifications mark no material departure from the salient features of the invention as expressed in the appended claims.

In the drawing:

40 Fig. 1 is a side view of the can opener in operative position.

Fig. 2 is a plan view of the same.

Fig. 3 is a plan view of the can opener showing the cutter automatically thrown out 45 of operation by a reverse rotation of the crank arm.

Fig. 4 is a fragmentary bottom plan view of the cutter and gage roller in cooperative cutting relation with a can.

50 Referring to the drawing, 1 designates a table top, to which is rigidly secured by screws a base or bracket plate 2, having a centrally disposed strengthening rib 3, and

a vertical arm 4. The rib 3 is continued upwardly and centrally of the bracket arm 5 to strengthen the same. The bracket arm 4 is only employed when it is desired to attach the can opener to a wall instead of a table top. Where the can opener is to be used solely on a table top, the bracket arm 60 4 may be left off when manufacturing the device.

Intermediate the ends of the rib 3 is formed a circular enlargement or boss 5 into which is adapted to be screwed a pivot bolt 6. One end of an oscillating arm 7 is pivotally mounted on the bolt 6, while the other end of said arm is provided with an integrally formed bearing 8 for a vertical shaft 9 adapted to be rotated by a crank arm 10. 70

A spur gear 11 is rigidly secured to the shaft 9 so that when said shaft is rotated by the crank arm 10, the gear 11 will likewise be rotated and mesh with a gear 12 on a shaft 13, whereby said last-mentioned gear 75 and shaft are operated reversely to the direction of rotation of the gear 11.

The outer end of the base plate 2 is enlarged and provided with an elongated slot 14, in which is adapted to travel, in a horizontal plane, the bearing 8 on the end of the oscillating arm 7, the bearing being limited in its movements by the opposite ends of said slot. 80

Rigidly connected to the lower end of the 85 shaft 9 is a collar 16. A circular rotary cutter blade 17 with a beveled edge is slipped on the shaft 9 abutting the lower side of the collar 16 and removably secured in any approved manner to said shaft. The 90 blade is maintained in position against the collar by means of a washer 18 and a nut 19. A washer 20 is mounted on the shaft 9 between the collar 16 and the bottom face of the enlargement on the end of the base plate 95 2 in which the slot 14 is formed, said washers bearing against the underside of the walls of said slot.

Integrally formed upon the base plate is a vertical bearing sleeve 21 for the vertical shaft 13. A washer 22 spaces the collar on the gear 12 from the bearing 21. Upon the lower end of the shaft 13 is rigidly secured a gage roller 23, the bottom face of which is slightly spaced above the cutting edge of the 100 cutter 17. The roller 23 is knurled and 105

adapted to engage the bead 24 of the can 25, and cooperates with the rotary blade 17 to rotate the can while the blade 17 is making the cut in the can as shown in Fig. 1.

5 The can opener is shown in an inoperative position in Fig. 3, and in position for the inner wall of the bead 24 of the can to be placed in position against the knurled roller 23. When the crank arm 10 is rotated in the 10 direction indicated by the arrow in Fig. 2, the gear 11 is rotated and the teeth of said gear will engage with the teeth on a rack 26 causing the bearing 8 to travel in the slot 14 and oscillating the arm 7. The rack 26 15 is formed integrally with a bracket 27 cast integrally with the base plate, but it may be otherwise formed. When the gear 11 is moved sufficiently to be released from the rack 26 and engage the gear 12, a continued 20 operation of the crank arm 10 and therefore rotation of the gear 11 will cause rotation of the gear 12. While the bearing 8 is moving towards the end of the slot 14, the cutter 17 is moving towards the outer cylindrical 25 wall of the can 25, with the gage roller 23 in engagement with the inner surface of the bead 24. When in this position, the bead 24 is clamped between the revolving knurled roller 23 and the collar 16, with the blade 17 30 cutting through the wall of the can just beneath the head of the can. The rotation of the knurled roller 23 and the collar 16 causes the can to be rotated while the knife 17 is cutting through the wall of the can. 35 and the pressure of the roller 23 and the collar 16 on the bead 24 aids in maintaining the bearing 8 against the end of the slot 14.

It will be seen from this, that the cutter is not only automatically moved to a cutting 40 position relative to the can, but the bead is automatically clamped between the roller 23 and the collar 16 by rotation of the crank in a direction indicated by the arrow in Fig. 2.

When it is desired to release the can, a reverse movement of the crank arm 10, as indicated by the arrow in Fig. 3, will cause the teeth of the gear 11 to be disengaged from the gear 12 and to be engaged with the teeth of the rack 26 by a slight rearward pull on 50 the crank arm 10, and since the gear 11 is being rotated by the arm 10, the bearing 8 will be moved to the opposite end of the slot, away from the can.

By reason of the fact that the cutter is 55 withdrawn away from the gage roller 23 when in the inactive position, it will be possible to insert the bead of a can in proper position and then swing the arm with the cutter into cutting position.

60 What is claimed is:—

1. In a can opener, a rotary cutter or knife, a gage roller for engagement with the inner wall of the bead of the can, cooperating means for causing the cutter and roller 65 to be simultaneously rotated in opposite di-

rections, and means engageable with the cooperating means upon rotation of the cutter for automatically moving the cutter into cooperative relation with the roller for cutting the can, said means, when the cutter is reversely rotated, automatically moving the cutter to an inoperative position. 70

2. In a can opener, a rotary cutter or knife, a gage roller for engagement with the inner wall of the bead of the can, cooperating 75 means for causing the cutter and roller to be simultaneously rotated in opposite directions for cutting the wall of the can, and means engageable with the cooperating means upon the rotation of the cutter in a reverse direction 80 for moving the cutter out of cooperative relation with the roller and can. 85

3. In a can opener, a rotary cutter or knife, a gage roller for engagement with the inner wall of the bead of the can, intermeshing 90 gears for causing the cutter and roller to be simultaneously rotated in opposite directions and means for positively throwing one of the gears out of mesh with the other gear when said cutter is rotated in a reverse direction. 95

4. In a can opener, a rotary cutter or knife, a gage roller for engagement with the inner wall of the bead of the can, and an arm carrying the rotary cutter adapted to be moved in one direction for swinging the cutter into 100 cooperative relation with the roller for cutting the can upon rotation of the cutter, said cutter being released by the reverse movement of said arms. 105

5. In a can opener, a rotary cutter or knife, a gage roller for engagement with the inner wall of the bead of the can, and an arm carrying the rotary cutter adapted to be oscillated for swinging the cutter into cooperative 110 relation with the roller for cutting the can upon rotation of the cutter in one direction, said arm upon a reverse rotation of the cutter being oscillated to move the cutter to an inoperative position. 115

6. In a can opener, a rotary cutter or knife, a gage roller for engagement with the inner wall of the bead of the can, an arm carrying the rotary cutter adapted to be oscillated for swinging the cutter into cooperative 120 relation with the roller for cutting the can upon rotation of the cutter in one direction, said arm upon a reverse rotation of the cutter being oscillated to move the cutter to an inoperative position, and means to limit the movement of the arm in either direction. 125

7. In a can opener, a rotary cutter, a swingable arm upon which the cutter is mounted, a gage roller for engagement with the inner wall of the bead of the can, a gear carried by the roller, a gear carried by the arm and adapted to mesh at times with the gear carrier by the roller, and means cooperating with the first-mentioned gear to cause the arm to swing the cutter into coop- 130

erative relation with the roller upon rotation of the cutter, and likewise to cause the gears to intermesh for causing simultaneous rotation of the cutter and gage roller but in opposite directions.

8. In a can opener, a base plate, an arm pivotally mounted on the base plate for oscillation in a horizontal plane, a shaft rotatably mounted on the free end of the arm and provided with a gear and a cutter, the base plate being provided with an elongated slot at one end in which is adapted to travel the shaft on the free end of the arm, a shaft mounted for rotation on the end of the base plate and provided with a gear, a gage roller on the second shaft for engagement with the inner wall of the bead of the can, and a rack on the base plate engageable with the gear on the swingable arm for swinging the arm upon rotation of the shaft thereon to cause the gears to intermesh and the cutter to move into cooperative cutting relation with the can.

9. In a can opener, a base plate, an arm pivotally mounted on the base plate for oscillating in a horizontal plane, a shaft rotatably mounted on the free end of the arm and provided with a gear, a cutter, and a crank, the base plate being provided with an elongated slot at one end in which is adapted to travel the shaft on the free end of the arm, a shaft mounted for rotation on the end of the base plate and provided with a gear, a gage roller on the second shaft for engagement with the inner wall of the bead of the can, and a rack on the base plate engageable with the gear on the swingable arm for swinging the arm upon rotation of the shaft thereon to cause the gears to intermesh and the cutter to move into cooperative cutting relation with the can.

10. In a can opener, a base plate, an arm pivotally mounted on the base plate for oscillation in a horizontal plane, a shaft rotatably mounted on the free end of the arm and provided with a gear, a cutter, and a hand crank, the base plate being provided with an elongated slot, a shaft mounted for rotation on the base plate at one side of the slot and provided with a gear adapted to mesh with the gear on the arm, a gage roller on the second shaft for engagement with the inner wall of the bead of the can, and a rack on the base plate engageable with the gear on the arm for swinging the arm upon rotation of the shaft thereon to cause the gears to intermesh and the cutter to move into cooperative cutting relation with the can, and when the shaft on the swingable arm is rotated in a reverse direction the said cutter is automatically thrown out of

cooperative relation with the gage roller and the can.

11. In a can opener, a rotary cutter, a swingable arm upon which the cutter is mounted, a gage roller for engagement with the inner wall of the bead of the can, a gear carried by the arm, a rotatable collar on the arm operated by said gear and adapted to cooperate with the gage roller for clamping the bead, a gear for operating the gage roller, a rack engageable with the first-mentioned gear for causing swinging of the arm upon rotation of said gear whereby the gears are caused to mesh for simultaneous rotation of the roller and cutter, the rotation of the gears when in mesh oscillating the free end of the arm to carry the cutter into cutting relation with the can, and the collar and roller into clamping relation with the bead whereby said can is rotated.

12. In a can opener, the combination of a base plate, an arm pivoted thereto and projecting therefrom, said base plate carrying a gear, a rack adjacent the gear, and a gage roller on the same shaft with the gear, and said arm carrying a shaft provided with a cutter, a gear to mesh with the first-mentioned gear, a collar to cooperate with the gage roller, and a crank handle for operating the shaft on the arm.

13. In a can opener, a rotary cutter or knife, a gage roller for engagement with the inner wall of the bead of the can, cooperating means for causing the cutter and roller to be simultaneously rotated in opposite directions, and automatic means for causing the cutter to be moved into cooperative relation with the roller for cutting the can when the cutter is rotated, said means, when the cutter is reversely rotated, causing the cutter to be automatically moved to an inoperative position.

14. In a can opener, cooperating means for cutting the can, comprising a rotary cutter or knife and a gage roller for engagement with the inner wall of the bead of the can, means for causing simultaneous rotation of the cutter and roller, and automatic means for causing one member of the cooperating cutting means to be moved into an operative relation with the other member of the cooperative cutting means, said automatic means, when the cutter and roller are reversely rotated, causing the movable member of the cooperative cutting means to be moved to an inoperative position.

In testimony, that I claim the foregoing as my own, I have hereto affixed my signature.

ROBERT H. WALLER.
